UNITED STATES PATENT OFFICE.

DAVID SELLERS, OF WINFIELD, KANSAS.

NAPKIN-HOLDER.

No. 872,852.

Specification of Letters Patent.

Patented Dec. 3, 1907.

Application filed July 18, 1906. Serial No. 326,784.

To all whom it may concern:

Be it known that I, DAVID SELLERS, a citizen of the United States, residing at Winfield, in the county of Cowley and State of Kansas, 5 have invented new and useful Improvements in Napkin-Holders, of which the following is a specification.

My invention relates to clasps, and its primary object is to provide a device of this 10 character which is especially adapted for securing a napkin upon the person, which is simple and durable, and which may be manufactured and sold at a comparatively low cost. 15 With the above and other objects in view, the invention consists in the construction, combination and arrangement of parts hereinafter fully described, claimed and illustrated in the accompanying drawings, where- 20 in:

Figure 1 is a view in front elevation of a clasp constructed in accordance with my invention. Fig. 2 is a view in rear elevation thereof. Fig. 3 is a side elevation. Fig. 4 is 25 a vertical central section therethrough. Fig. 5 is a view in front elevation of the body of the clasp. Fig. 6 is a view in front elevation of the jaw of the clasp.

Referring to the drawings by reference 30 characters, A designates the body, B the jaw and C the spring of my improved clasp.

The body is designed to be constructed of a single strand of wire, which strand is formed to provide parallel side bars 2, a lower connecting bar 3 and an upper connecting bar 4. The ends of the strand, which form the upper connecting bar 4, are arranged in overlapped relation. The ends are flattened to provide enlarged portions 5, the purpose of 35 which will be presently set forth. The side bars 2 are formed to provide eyes 6 which are arranged at points intermediate the ends of the bars, and which are provided for the purpose of receiving a pivot post 7. The ends of the 40 pivot post 7 project laterally beyond the side bars 2 and are flattened to provide enlarged heads which retain the pivot post in applied position. The jaw B is also constructed of a single strand of wire, which strand is formed 45 to provide parallel arms 8 and a connecting bar 9. The arms 8 are bent intermediate their ends to provide journals 10 through which passes the pivot post 7 to pivotally mount the jaw B upon the body A. The 50 connecting bar 9 of the jaw B and the arms thereof extend downwardly at a point below

the bar 3 of the body. The lower ends are formed to provide pointed hooks 11 which engage below the bar 3, as fully illustrated in the drawings.

A spring C is coiled upon the pivot post at a point intermediate the journals 10 of the jaw B, said spring retaining the arms 8 of the jaw in proper spaced relation. The ends of the spring C are contained in an upward direction, as at 12 and 13. The extension 12 of the spring C is coiled about the end of the strand forming the connecting bar 4 of the body A to retain the strand in body formation and is then continued upwardly beyond 70 said bar and formed to provide a hook 14, which provides means by which the clasp may be secured to the person. The extension 13 of the spring C is coiled about the connecting bar 9 of the jaw B, whereby said jaw 75 is normally retained in clamping position.

In practice, the connecting bar 9 of the jaw B is engaged and moved in the direction of the connecting bar 4 of the body A to permit the clasp to be applied to a napkin. The 80 clasp is applied to a napkin by inserting one edge of the napkin between the body A and jaw B. After the clasp has been applied, the jaw B is released to permit the spring C to force the hooks 11 in engagement with the 85 napkin and permit the arms 8 to clamp the napkin firmly between them and the body A, after which the napkin may be secured to the person through the medium of the hook 14.

From the foregoing description taken in connection with the accompanying drawings, the construction and mode of operation of the invention should be understood without a further extended description.

Changes in the form, proportions and minor details of construction may be made within the scope of the claims without departing from the spirit or sacrificing any of the advantages of the invention.

Having fully described and illustrated my invention, what I claim is:

1. A clasp comprising a body constructed of a single strand of wire, the ends of the strand being enlarged and overlapped, a 105 pivot post secured to the body, a jaw constructed of a single strand of wire and pivotally mounted upon the pivot post, and a coiled spring mounted upon the pivot post and having one of its ends wrapped about 110 the overlapped ends of the strand of which the body is formed and thence extended and

formed to provide a hook, the other end of the strand engaging the jaw.

2. A clasp comprising a body constructed of a single strand of wire, the ends of the strand being enlarged and overlapped, a jaw pivotally mounted upon the body, and a spring, one end of the spring being wrapped about the overlapped ends of the strand.

3. A clasp comprising a body constructed of a single strand of wire, the ends of the

strand being overlapped, a jaw pivotally mounted upon the body, and a spring, one end of the spring being wrapped about the overlapped ends of the strand.

In testimony whereof, I affix my signature 15
in presence of two witnesses.

DAVID SELLERS.
